VAPOR PHASE CRACKING

Charles B. Buerger, Pittsburgh, Pa., assignor to
Gulf Refining Company, Pittsburgh, Pa., a cor-
poration of Texas

Application June 4, 1926, Serial No. 113,778

5 Claims. (Cl. 196—61)

This invention relates to vapor phase cracking; and it comprises a method of cracking petroleum oils as vapor wherein oil to be cracked is contacted with hot cracked oil vapors to distil it and free it 5 of non-volatilizable matters, the mixed oil vapors thus produced are subjected to partial refluxing condensation and the condensate so formed is utilized to produce said cracked oil vapors; all as more fully hereinafter set forth and as claimed.

10 The advantages of cracking in the vapor phase are well recognized but there is difficulty in providing efficient method and means for accomplishing this in any continuous way. In the art, the expressions low boiling oils and light oils 15 are equivalent and the expressions high boiling oils and heavy oils are equivalent. Most petroleum oils used for cracking carry heavy ends; on vaporization there is not a complete vaporization and there is a production of carbon-rich oils, 20 tars and coke. By direct introduction of any such oil into a heating zone at a cracking temperature not all of it vaporizes; there is formed a residue of coke. By the expedient of distilling the oil in a still and superheating the vapor, 25 true vapor phase cracking can be performed; but this is an additional complication and expense.

It is the purpose of the present invention to 30 provide a simple and direct method of effecting cracking in the vapor phase with the use of simple organizations of apparatus. To this end I take the oil to be treated and bring it into effective large area contact with hot cracked oil 35 vapors coming from a suitable cracking apparatus. This lowers the temperature of the cracked oil vapors and vaporizes the volatilizable portions of the charge oil, producing a residuum which is discarded from the system. In a good embodiment of the present invention the mixture of oil vapors, those coming from the charge 40 oil and from the cracking device, are passed into a device of the general nature of a refluxing column wherein the heavier portions of the cracked oil vapors and of the charge oil vapors are condensed. The residual uncondensed vapors of 45 lighter oils, coming both from the charge oil and from the cracking device, go forward through a water-cooled condenser to be condensed and treated in the usual manner. The mixture of liquid oils produced in the refluxing column as 50 described is sent to the cracking device wherein it is vaporized and cracked. The operation may be under as much pressure at any point as may be desired; but ordinarily I provide merely as much pressure as is necessary to force the oil 55 and vapor through the cracking device. This

being commonly tubular in construction and of relatively great length and small diameter, sometimes rather high pressures are necessary at its inlet to overcome friction, etc. In performing the vaporizing and condensing operations specified I commonly provide a tower like apparatus of the general nature of a column or reflux tower but divided into two sections, an upper and a lower which are in vapor communication, with means at the bottom of the upper section for intercepting 5 condensed liquid at that point. Into the lower section I discharge hot vapors coming from the cracking apparatus and also introduce the charge oil to be treated. From the base of this lower section I remove unvolatilized residuum 10 which is sent out of the system. The cracked oil vapors, now somewhat cooled, and the vapors derived from the charge oil go together into the base of the upper section wherein they are subjected to a reflux condensing action in an ordinary way with production of a condensate and of uncondensed vapors which go forward to a final water-cooled condenser for appropriate treatment. The condensate from the base of the upper section is taken by pumping means and 15 delivered to the inlet of a cracking coil in a suitable furnace. Ordinarily I pass the oils through a vaporizing preheater en route; this preheater being supplied with heat from the waste gases from the cracking furnace. 20

Since the condensate formed in the tower is at a lower temperature than is desirable for oil fed to the cracking coils, I provide a reboiler through which the oil is circulated, thereby not only heating the oil but freeing it of any gasoline it may 25 retain at refluxing temperatures. 30

In one particular case in dealing with a dirty gas oil or a light fuel oil, the oil was charged into the lower section of such a tower as that described, this being maintained at a temperature 40' of approximately 1,000° F. Into this section, hot cracked oil vapors were supplied. About 90 per cent of the liquid oil charged into this section was vaporized and carried out of the lower section into the upper section. At the top of the 45 upper section a vapor temperature of about 300° F. was obtained. Oil from the base of the upper section was circulated cyclically to, through and from a heater so as to maintain a temperature of about 600° F. in the recirculated oil delivered 50 to the tower. The condensed oils from this upper section were placed under pump pressure of about 350 pounds and forced forward at a temperature of about 400° F. through a preheater and into a tubular cracking device wherein there was 55

maintained a temperature of about 1100° F. The initial pressure in the particular tubular cracking system used was, as stated, about 350 pounds while at the discharge end of the pressure was about 15 pounds.

In the accompanying illustration I have shown, more or less diagrammatically, an embodiment of apparatus elements within the purview of the present invention and susceptible of use in the 10 performance of the described process. The showing is mainly in vertical section with certain parts in elevation.

In the structure shown, charge oil is taken from storage tank 1 by pump 2 and forced through line 3 into the lower section 4 of a two-part tower. As shown, this section is provided with the usual 15 surface-giving devices. The charge oil is introduced near the top of the section. From this section vapors are taken by by-pass 4a into an upper section 5 of much the same construction. This upper section serves however as a reflux condensing device while the lower section described is a vaporizing device. Condensate produced in this upper section is taken by line 6 to a 20 charge tank 7 whence it goes via pump 8 to a surge tank 9. From the surge tank oil passes forward past valve 10 and meter 11 into a pre-heating and vaporizing coil 12 located in the off-take of a furnace chamber. From the preheater 25 the oil passes through diagrammatically shown cracking tubes 13. In practice many of these tubes may be arranged in series and in parallel but for convenience in illustration I have shown merely one tube. From the cracking tubes the cracked oil vapors pass into an expansion chamber or tube 14 and thence back to the bottom of the described lower section of the tower (4). Returning to the reflux condenser (5), uncondensed 30 vapors pass from its top through the usual condenser 15. The condensate goes into trap tank 16, whence gas is vented through 17 to any suitable place of use. Condensed naphtha from the trap tank goes to storage tank 18. In order to 35 take oil out of this part of the system at a relatively high temperature, positively freed of gasoline and light oils, I circulate oil from the base of the section through a reboiler. As will be seen, liquid oil is taken from the base of the upper section through 19 by pump 20 and forced through 40 heating coil 21, thence returning to the base of the upper section through return pipe 22. Heat for the whole system is furnished by furnace chamber 23 which may conveniently be fired by gas from 17. As this furnace is shown the cracking 45 coil assemblage is in front of a bridge wall 24, back of which are located the stated preheating coils and the heater coil for the circulating system, thus exposing the cracking coil to radiant heat from the furnace and shielding from radiant 50 heat the preheating and vaporizing coils 12 and heater coil 21 of the reflux circulatory system. Furnace gases finally go away through offtake 25. Unvolatilized residuum from the base of the lower section is continuously taken through cooler 26 55 by pump 27 and sent to residuum tank 28. Imperforate partition 29 separates the upper and lower sections of the two-part tower.

What I claim is:—

1. In the cracking of petroleum oils, the process 60 which comprises cracking an oil in the vapor phase, intimately contacting the hot cracked vapors with charge oil thereby vaporizing the vaporizable constituents thereof, removing and discarding all liquid residuum of the charge oil, sub- 65 jecting the mixed vapors to reflux condensation

in a refluxing zone, removing and condensing uncondensed vapors, withdrawing condensate from said refluxing zone, heating the same to a temperature of about 600° F. and returning it to the refluxing zone, and subjecting condensate from said refluxing zone to vapor phase cracking for the production of additional hot cracked vapors for intimate contact with further quantities of charge oil.

2. In the cracking of petroleum oils, the process 10 which comprises intimately contacting hot cracked oil vapors at a temperature of about 1000° F. with charge oil thereby vaporizing vaporizable constituents of the charge oil, removing and discarding all liquid residuum of the 15 charge oil, subjecting the mixed vapors to rectification in a refluxing zone and there condensing all fractions heavier than gasoline, removing and condensing uncondensed vapors, removing condensate from the refluxing zone, heating the same 20 to about 600° F. and returning it to the refluxing zone, and transmitting condensate from said refluxing zone to a vapor phase cracking zone maintained at a temperature of about 1100° F. for the production of additional hot cracked vapors for 25 contact with further quantities of charge oil.

3. The process as defined in claim 2 wherein the hot cracked vapors are expanded prior to contact with the charging oil.

4. In the cracking of petroleum oils, the process 30 which comprises continuously passing the oil in a confined stream through a heating zone and there vaporizing the oil; passing the vaporized oil through a second heating zone and there heating the oil vapors to a temperature of the order 35 of 1100° F.; maintaining the oil and vapors, throughout their heating, under pressure not substantially greater than sufficient to effect their passage through the heater tubes; intimately contacting the stream of heated vapors with a 40 stream of fresh oil, thereby effecting heat interchange between the two streams and vaporizing a portion of the fresh oil, said contacting being effected under a pressure not greatly in excess of atmospheric pressure; discharging from the 45 process the liquid residue from said contacting of heated vapors and fresh oil; subjecting the remaining vapors to partial condensation; heating the higher boiling condensate from said partial condensation to a temperature of the order of 50 600° F. to free it of any constituents which may not require further cracking; and utilizing the stripped heavy condensate as the oil feed to the first mentioned heating zone.

5. In the cracking of petroleum oils, the process 55 which comprises continuously passing the oil in a confined stream through a heating zone and there vaporizing the oil; passing the vaporized oil through a second heating zone and there heating the oil vapors to a temperature of the order 60 of 1100° F.; intimately contacting the stream of heated vapors with a stream of fresh oil, thereby effecting heat interchange between the two streams and vaporizing a portion of the fresh oil; discharging from the process the liquid 65 residue from said contacting of heated vapors and fresh oil; subjecting the remaining vapors to partial condensation; heating the higher boiling condensate from said partial condensation to a temperature of the order of 600° F. to free it of 70 any constituents which may not require further cracking; and utilizing the stripped heavy condensate as the oil feed to the first mentioned heating zone.
